LOUIS BESSIÈRE, OF PARIS, FRANCE, ASSIGNOR TO PAUL DURAND, OF NEW YORK, N. Y.

DESIGN FOR A DRINKING VESSEL.

SPECIFICATION forming part of Design No. 36,123, dated October 28, 1902.

Application filed September 16, 1902. Serial No. 123,659. Term of patent 7 years.

To all whom it may concern:

Be it known that I, LOUIS BESSIÈRE, a citizen of the Republic of France, and a resident of the city of Paris, in the department of 5 Seine, France, have invented and produced a certain new, original, and ornamental Design for a Drinking Vessel or Similar Article, of which the following is a specification.

My design is illustrated in the accompanying drawing, referred to herein, which shows a drinking vessel with my design thereon.

A band or border *a* extends around the vessel near the brim thereof, and consists of leaf-like ornaments *a'* between border-lines *a²* and 15 ornaments consisting of the collar *b* and streamers *c*.

At the lower part of the vessel is a C-shaped scroll *d*, inclosing leaves *f*. Above this scroll is a smaller reversed scroll *g*, of similar shape, 20 having a leaf *i* above it. Small ornaments *h* and *h'* are located at various intervals along the scrolls. The ornamentation thus described is repeated a number of times around the vessel, and between each figure is an or-

namentation composed of a scroll *l*, terminating at its upper end in a leaf *m'* and having a still smaller scroll *k* above it surmounted by a leaf *n*, similar to *i*, with another leaf *m* at one side. Small scrolls *e* and *e'* proceed from the base of the large scroll *d*, embracing 25 leaves *i*.

The body of the vessel X, upon which the ornamentation is displayed, is otherwise plain. The shape of the vessel, however, is not new, and it will be apparent that the ornamentation above described may be placed on differently-shaped vessels. 30

What I claim is—

The ornamental design for a drinking vessel or a similar article substantially as herein 35 shown and described.

Signed at the city of Paris, in the Department of Seine, this 31st day of July, 1902.

LOUIS BESSIÈRE.
